UNITED STATES PATENT OFFICE.

OSMOND T. BELCHER, OF LOS ANGELES, CALIFORNIA.

WOOD-WEAVING LOOM.

1,382,816.

Specification of Letters Patent. Patented June 28, 1921.

Application filed November 7, 1919. Serial No. 336,395.

To all whom it may concern:

Be it known that I, OSMOND T. BELCHER, a citizen of the United States, residing at 5715 Bandera street, Los Angeles, in the county 5 of Los Angeles and State of California, have invented new and useful Improvements in Wood-Weaving Looms, of which the following is a specification.

My invention relates to improvements in 10 machines for weaving together into a fabric thin ribbons of wood; an object being to provide a wood weaving machine for weaving together closely a warp and a weft composed of ribbons of wood having a proper 15 width so as to form a continuous sheet of the fabric of any desired width, a second object being to provide a wood weaving machine for weaving thin strips of wood comprising the warp and weft of a wooden 20 fabric resulting therefrom and having a means for gluing the warp to the weft where the strips cross and lay upon each other; a third object being to provide a shuttle for the weft particularly adapted to handling 25 the same; a fourth object being to operate a gluing device in such a weaving machine whereby that surface only of the warp is treated with glue which makes a cross contact with the strips of the weft. Other objects will appear hereinafter.

A plan view of the device, having a longitudinal central portion broken away, comprises Figure 1, Fig. 1^A, and Fig. 1^B.

Fig. 2 is a longitudinal view in sectional elevation of the device taken on the line A, A, Fig. 1^A.

Fig. 3 is a side elevation of a carriage and mechanism for operating a shuttle looked at in the direction of the arrows B shown in 40 Fig. 1^A and Fig. 4.

Fig. 4 is an end elevation of a carriage and mechanism for operating a shuttle as shown in Fig. 3 together with part of the device positioned beyond or toward a rear 45 end of the device from the shuttle as looked at in the direction of the arrow C Fig. 1^B.

Fig. 5 is a view of the heald frames for alternately crossing the warp as looked at from the rear end of the device and in the 50 direction of the arrow D Fig. 2.

Fig. 6 is an enlarged sectional elevation of a glue carrier operating on the top side of the warp.

Fig. 7 is an enlarged sectional elevation

of a glue carrier operating upon the under side of the warp.

Fig. 8 is a fragmentary detail view of a means for feeding glue to the roller of the under glue carrier as shown in Fig. 7.

Fig. 9 is a plan of a tension spring used 60 at the feed end of the device looked at in the direction of the arrow I Fig. 2.

Fig. 10 is a view of the outer end of the spring as shown in Fig. 9 with the two 65 blades separated.

Fig. 11 is a view in front elevation of guide means for the warp showing the staggered arrangement thereof.

Fig. 12 is a side elevation of the central 70 part of the device looked at in the direction of the arrow E Fig. 1 showing the opposite side of the device from that shown in Fig. 4.

Fig. 13 is an enlarged cross section of a shuttle showing a clamping means for the weft strips in an open position.

Fig. 14 is a cross section of a shuttle as shown in Fig. 13 with a clamping means for the weft strips in a closed position.

Fig. 15 is a top view of a fragmentary section of a shuttle showing the clamping 80 means for the weft strips.

Fig. 16 is an elevation of a shuttle showing clamping means for the weft strips and looked at in the direction of the arrow F, Fig. 14.

Fig. 17 is a detailed view partly in section of a group of reels for carrying the warp, showing a means for taking out individual reels.

Fig. 18 is a detailed view of one end of a 90 feeder clamp showing a mechanism for its operation.

Fig. 19 is a detailed view of one of a pair of holding clamp cam mechanisms.

Fig. 20 is a diagram of the different 95 operations of the device showing a complete cycle thereof to be used hereinafter for explaining the operation of the invention.

Fig. 21 shows in frontal elevation, a double acting cam for putting a shuttle, also a section of a rock arm which carries the shuttle, and in dotted lines a roller and pin extending from the arm into a groove in the cam.

The wood weaving machine herein set 105 forth embodying the principles of my invention comprises a means for feeding the warp formed of ribbons of wood and lo-

cated at what is hereinafter termed a head end of the device and as indicated by arrow G, see Fig. 2, a tension and guide means for controlling the feed of the warp positioned 5 immediately following the feed means and indicated by an arrow H, a healding means for alternately crossing alternate strips of warp following the guide means located about the center of the device, a gluing 10 means operating on the warp and a shuttle for carrying the weft operating in the device immediately following the healding means and clamping means for properly holding and pulling the wooden fabric, being positioned in what is hereinafter termed 15 a tail end of the device.

More specifically a frame for supporting the various functioning parts of the device comprises base members 1, 1, and having a 20 superstructure formed of the members 2, 2—3, 3—4, 4—5, 5—6, 6—7, 7—8, 8— and 9, 9—.

At the head end of the device is mounted 25 a gang of reels 10 carrying wood ribbons 11 forming half of the warp. Below the reels 10 and staggered relative to their vertical position is a second gang of reels 12 carrying wood ribbons 13 forming the other half of the warp. The two gangs of reels are supported from cross bars 14 which are formed 30 integral with the uprights 2, 2 of the frame.

With reference to Fig. 17, the reels are formed of two disks 15 spaced by a hub 16 which carries a central bore 17. The reels 35 are supported by the arms 18 extending downwardly from the cross bars 14. A bearing is formed at the lower end of each arm having an opening 19 in the top side, the bearings in the arms being adapted to slidably carry stub shafts 20. The stub shafts 40 are of such length as to extend beyond the face of the arms 18 and are adapted to the bore 17 of the reel hubs forming a bearing upon which the reels rotate.

45 A groove 21 is cut at the center of each shaft. A finger 22 is positioned with a lower end fitted to the groove 20 of each shaft through the opening 19, the fingers being pivotally mounted vertically above 50 each bearing by a cap screw 23 to the cross bar 14. Below the bearing on each of the arms 18 is a spring pocket 24 carrying a coil spring 25 which bears at its top end against a ball 26, the lower end of the 55 spring being carried by an adjusting screw 27, the balls 26 being adapted to partially enter the grooves 21 of the stub shafts to keep the shafts from drifting.

The warp running from the reels 10 passes 60 through the outer ends of tension springs 28, under a roller 29, through guides 30 and under a roller 31. The warp running from the reels 12 passes through tension springs 32 over a roller 33 through guides 34 and 65 over a roller 35.

There is a tension spring for each strip of the warp they being formed of an inner blade 36 and an outer blade 37. The inner blade 36 extends beyond the outer end of the outer blade, the extension being bent 70 upwardly so that it is on the same plane with the outer blade. The inner blade is also formed with ears 38 at its outer end adapted to be bent up over the end of the outer blade so that the outer blade is slidably carried by the inner blade. The outer blade is notched as shown in Fig. 10 forming a central extending tongue 39. The inner blade has a slot 40 adjacent to its outer end and from the inner edge of the slot 40 80 the blade is bent upwardly the thickness of the blade and outwardly so that when the outer blade is slipped under the ears 38 of the inner blade the tongue 39 will partially close the slot 40.

85 Between the members 5, 5 of the frame is positioned a cross bar 41 for carrying the upper set of tension springs 28 adapted to operate upon the warp strips 11 and between the members 4, 4 of the frame is fixed a second cross bar 42 carrying the lower set of tension springs adapted to operate upon the warp strips 13. The cross bars 41 and 42 are formed of a base member having two outwardly extending members 43 and 44. 90 The member 43 carries a rectangular slot for each tension spring through which the spring is passed, the inner blade 36 being screwed to the cross bar by a screw 45 while the outer blade remains slidably mounted in 100 the member 43. Through the extension 44 is screwed an adjusting screw 46 having a set nut 47 the inner end of which bears against the end of the outer blade of the tension spring.

105 The roll 29 is rotatably mounted transversely of the warp strips 11 in a vertical member 49 extending upwardly from the member 3 of the frame 1. The roll 33 is rotatably mounted transversely of the warp strips 13 in the vertical member 49, the rolls 29 and 33 being positioned to bear evenly upon all the warp in the upper and lower sets respectively.

110 The guides 30 and 34 are rectangular in form and have belled ends as shown to prevent the warp from cutting on the edges of the openings, the inner measurement of each guide opening being slightly greater than the width and thickness of the warp strips. These guides are too wide to be set side by side on the same level and so are set on two levels staggered as shown in Fig. 11, the inside edge of one guide slightly overlapping the inside edge of the next so that the warp strips are brought closely together. The two sets of guides are carried by a cross bar 48 mounted between the members 5 of the frame.

115 The rolls 31 and 35 are rotatably mounted 120

in a vertical member 50 fixed to the member 3 of the frame, they being positioned to bear properly upon the upper and lower sets of the warp strips respectively.

5 The uprights 6, 6 extending vertically from the base 1 of the frame have channels in their inside faces adapted to form guides for two heald frames 51 and 52. The frame 51 is composed of the side members 10 53, 53, a top bar 54 and a bottom bar 55, the second frame being like the first comprising the side members 56, 56 and a top bar 57 and a bottom bar 58. The frame 51 carries, extending downwardly from the top bar 54, 15 arms 59 which reach nearly to a central line between the top and bottom bars there being an arm positioned to each alternate strip of the warp, and extending upwardly from the bottom bar 55 are like arms 60 having a 20 length extending them nearly to the end of the arms 59, there being a space between the ends of the two arms for carrying a strip of the warp, each set of arms in the frame registering on vertical lines.

25 Extending downwardly from the top bar 57 of the frame 52 are other arms 61 like those of the frame 51 positioned between the arms of the frame 51 and reaching nearly to a central line between the top and bottom 30 bars, and from the bottom bar 58 are other like arms 62 extending upwardly and reaching nearly to the end of the downwardly extending arms 61 and registering therewith on vertical lines so that the arms 61 and 62 35 will carry alternate strips of the warp.

The arms 59 and 60 of the frame 51 are formed at their inner ends with a rounded portion 63, 63 extending toward the head end of the device and the arms 61 and 62 of 40 the frame 52 are formed at their inner ends with a rounded portion 64, 64 extending toward the tail end of the device. The arms are slightly narrower than the strips of the warp and the frames are adapted to pass 45 each other with the rounded portions 63 and 64 passing in a vertical line. The inner ends of the arms are otherwise so formed that the strips of warp will always be bent over a properly rounded surface.

50 The frames are operated vertically by a rock arm 65 fixed to a rock shaft 66 being connected with the frame 51 by a link 67. The rock shaft 66 is operated by a shaft 68 rotatably mounted transversely of the frame 55 and carrying a cam plate 69 having a forked cam groove 70. A yoke 71 is mounted astride the shaft 68 having a pin and roller 72 for engaging the groove 70 of the cam. A downwardly extending portion 73 of the yoke 71 60 carries a rack which engages a gear 74 on the rock shaft 66. The rack 73 is kept in mesh with the gear 74 by a roller guide 75 on the back side of the rack, the rock shaft 66 and roller 75 being mounted in a stand- 65 ard 76. The rock arm 65 is connected to the

frame 51 by a link 67 and to the frame 52 by a link 67A.

Facing the device at the head end thereof, one side shall be hereinafter designated as a right hand side and the other side as a left hand side.

A driving shaft 78 for the device is mounted in a bearing 79, 80, 81, on the right hand side. The driving shaft carries a pinion 82 which meshes with the gear wheel 83 75 fixed upon the transverse shaft 68. Toward the rear end of the device on the shaft 78 is fixed a cam 84, a cam 85, a cam 86, a cam 87 and a cam 88. On the left hand side of the device from the driving shaft is mounted upon the transverse shaft 68 a bevel gear 89.

A longitudinal shaft 90 is mounted in bearings 91 and 92 and carries a pinion gear 93 meshing with the gear wheel 89. The 85 shaft 90 carries a cam 94, a cam 95 and a cam 96 and a cam 97.

The drive shaft 78 runs clockwise, the transverse shaft 68 runs contra-clockwise and the shaft 90 runs contra-clockwise. 90

The cams 84, 85, 87 and 88 respectively, on the shaft 78 are identical in form and throw to the cams 94, 95, 96 and 97 respectively, on the shaft 90 except that the two shafts are turning in opposite directions and the 95 cams are adapted to work together in pairs on the oppositely turning shafts.

Carried upwardly from the base are two vertical members 98, 98, at the top of which and transversely of the device is fixed a beam 100 99 forming a top stationary member of a weft clamp 100 and a second beam 101 beside the beam 99, and spaced properly therefrom, forming a top stationary member of a holding clamp 102. Below the stationary 105 beam 99 is positioned a beam 103 having its ends extending through guides 104 in the vertical members 98, 98 being mounted in the guides to move vertically. Links 105, 105 are pivotally connected to each end of the 110 beam 103 and extend downwardly and are pivotally connected to horizontal rock arms 106, 106, the inner ends of which are pivotally connected to the upright members 98, 98. The arms 106, 106 extend outwardly 115 over the cam 84 on the right hand side and the cam 94 on the left hand side and each carries a wheel 107, 107 adapted to bear upon each of the cams so that the beam 103 will be raised evenly by the operation of the two 120 cams and bear with pressure against the stationary beam 99. Below the stationary beam 101 is a vertically movable beam 108 having its ends slidably mounted in slots 109, 109 in the vertical members 98, 98 and adapted 125 to form a clamping means with the stationary member 101. Links 110, 110 are pivotally connected to the outer ends of beam 108, the lower ends of the links being pivotally connected to horizontal rock arms 130

111, 111, the inner ends of the rock arms being pivotally connected to the vertical members 98, 98, their outer ends extending out over the cam 85 on the right hand side and 5 the cam 95 on the left hand side and carries rollers 112, 112, which bear upon the cams so that by a rotation thereof the beam 108 will be raised evenly and bear against the stationary beam 101.

10 A pair of vertically disposed arms 113, 113 are pivotally connected with the base 1 by a transverse shaft 114. Across the top of the arms is fixed a beam 115 which forms an upper stationary member of a clamp 116 15 forming a part of a discharge mechanism for the device. Below the beam 115 is positioned a parallel beam 117 mounted to move vertically in slot 118, 118 in the arms 113, 113. Links 119, 119 are pivotally connected to 20 the outer ends of the beam 117 and extend downwardly, being pivotally connected at their lower end to horizontally disposed rock arms 120, 120, the rock arms being pivotally connected to the vertical arms 114, 25 114 and extending outwardly over the cam 88 on the right hand side and 97 on the left hand side and carrying the rollers 121, 121 for engaging the cams so that by their operations the beam 117 will be raised evenly 30 so as to bear with pressure against the stationary beam 116.

The pivotally mounted arms 113, 113 also carry rollers 122, 122 positioned to engage the face of the cam 87 on the right hand side 35 and 96 on the left hand side of the device so that by the operation of the cams the arms will be carried backwardly in unison thus carrying the feeder clamp 116 backwardly. Retractile springs 123, 123 are connected at 40 one end with the frame of the device forwardly of and at the other end with the arms 113, 113 whereby the arms may be pulled forward keeping the rollers 122, 122 in contact with the faces of the cams 87 45 and 96.

The strips of warp passing from the reels 10 and 11 at the head end of the device through the tension springs 28 and 32, under and over the rollers 29 and 33 through 50 the guides 30 and 34, under and over the rollers 31 and 35 is passed through between the ends of the arms 59 and 60 of the heald frame 51 and 61 and 62 of the heald frame 52 thence through between the weft clamp 55 100, the holding clamp 102 and the discharge clamp 116, the weft being woven in with the warp prior to its entrance into the weft clamp.

The weft clamp, the holding clamp and the 60 discharge clamp are notched as shown in Fig. 18, forming teeth in each member of each clamp, which register with each other, whereby, with a proper setting of the clamps, the teeth clamp always in the centers of the 65 warp, on one side, and the weft upon the

other side of the fabric. Such a construction is used so that the glue which might be pressed out from between the joints of warp and weft will not wet and gum up the clamps.

70 A shuttle carriage 125 is positioned at the right hand side of the device extending outwardly therefrom and backwardly of the heald frames. The carriage comprises a back plate 126 having a plurality of grooved top rollers 128, 128 and grooved bottom rollers 129, 129. Extending outwardly and downwardly from the plate 126 is an arm 130 at the outer end of which is rotatably mounted a weft reel 131 from which the weft 80 132 may be fed into the fabric to be produced by the device.

The weft passing from the reel 131 passes through a tension spring 133 over a roller 134 and through a guide 135, the guide and 85 roller being fixed to the back plate 125 by means of a bracket 136 which is formed integral therewith and the spring 133 is carried by an arm 137 which is also carried by the bracket 136. The tension spring 133 is 90 of the same design and operates in the same manner as the tension springs 28 and 32 through which the warp is fed.

The carriage 125 is mounted to swing longitudinally of the device being carried by 95 three sets of rock arms 138, 139 and 140, they being pivotally mounted at the base ends and pivotally connected to the carriage 125.

The main shaft 78 carries a cam 141 having a cam groove 142 within its face and an extending hub 143, the hub being mounted upon the shaft so that it will rotate therewith but loosely fitted in longitudinal key ways so that it may slide longitudinally of 100 the shaft. A stationary cam plate 144 is fixed positively to the bearing 79 of the main shaft having an irregular face formed to operate with a roller on the opposite side from the groove 142 of the cam 141 whereby that cam will be moved toward the rear end of the device along the shaft 78 by the rotation of the shaft. Bearing standards 145 and 146 extend outwardly from the plate 126 and carry slidably a screw 147, the screw 115 operating through a threaded bore of a gear wheel 148. At the lower end of the screw is fixed a yoke 149 which straddles the hub 143 of the cam.

Integral with the back plate 126 is an arm 149 extending outwardly toward the top of the cam 141 on which is rotatably mounted a guide wheel 150 which bears against the face of the cam so that by a rotation of the cam with the shaft the cam is moved toward the tail end of the device and through the guide roller 150 the carriage 125 is also carried in that same direction. A coil spring 151 fixed at one end to the shuttle carriage and at the other to a bracket 152 causes a 130

return movement of the shuttle carriage and cam. The rock arms 138, 139 and 140 are in pairs as shown in Fig. 4. When the roller in the face of the cam 141 engages the stationary cam plate 144 the cam 141 slides toward the rear on the shaft 78 and through the roller 150 pushes backwardly the plate 126. The rocker arms 138, 139 and 140 being in parallel sets cause the plate 126 and 5 the shuttle to maintain a level position, and the shaft 147 is therefore maintained in vertical alinement with the threaded bore of the gear wheel 148 throughout the travel of about one-half inch. The rods 138, 139 and 15 140, being pivoted at the top and bottom, will therefore not be snapped. The yoke 149 carries a roller and pin 153 which engages the cam groove 142 causing a vertical movement of the screw 147 and a rotation of the 20 gear wheel 148.

A shuttle comprising a T beam 154 is mounted with its cross member 155 disposed between the upper rollers 128, 128 and the lower rollers 129, 129 and its stem portion 25 156 pointing toward the tail end of the device. On the back of the shuttle is fixed a toothed rack 157 positioned to mesh with the gear wheel 148 whereby through the rotation of the gear wheel the shuttle is run 30 back and forward transversely through between the two sets of warp strips.

The outer end of the stem portion 156 is split forming a groove 158 having a very thin retaining wall above and below. A cam 35 shaft 159 is mounted upon the stem portion of the shuttle in bearings 160, 160 and 161, 161. See Figs. 13, 14, 15 and 16. Spring blades 162, 162 are fixed to the cross member 155 of the shuttle and pass outwardly 40 beneath the cam shaft. Their outer ends bearing upon the upper retaining wall of the groove 158. Cams 163 are formed on the shaft 159, there being one adapted to engage each of the plates 162, 162.

The cam shaft 159 has a lever 164 fixed to its outer end which when the shuttle is moved outwardly engages an arm 165 which throws the arm 164 downwardly causing the cams 163, 163 to pass under the center of 45 the shaft pressing the plates 162 downwardly thereby pressing the top wall of the crevice downwardly and partially closing the crevice. On the end of the outer pivot of the rock arm 106 which carries a roller 107, on 50 the right hand side of the device, is fixed a stiff rod 167 positioned to engage the lever 164 of the cam shaft 159, when the shuttle passes inwardly, and throws it upwardly thereby releasing the plates 162, 162 and 55 widening the crevice 158.

On the left hand side of the device is an outer shuttle bearing 169 which carries a pocket having a retractile spring 170 and adapted to receive the free end of the shuttle. The bearing is carried pivotally by a 60

pair of rock arms 171 pivotally mounted in the base 1. A double acting cam 172 is fixed on the transverse shaft 68 and carries a groove 173 adapted to engage a roller and pin 174 on one of the rock arms 171 whereby 70 the shuttle when entered into the bearing may be moved longitudinally of the device in unison with the movement of the carriage 125.

On the right hand side of the device and 75 mounted upon a standard 98 is a shear for cutting off, at a proper time, the strips of weft carried into the loom by the shuttle, comprising blades 176, 176 pivoted with the pin 177. The blades are carried between 80 two cams 178, 178 having arms 179, 179, the cams proper being formed on the inner ends of the rotatably mounted shaft portions marked 178, 178, in Fig. 4. A link 181 connects the two arms at their outer ends 85 and a rod 182 connects the lower arm 179 with a horizontal rock arm 183 which is pivotally mounted upon the standard 98, its outer end reaching out over the cam 86 and having a roller 184 rotatably mounted on its 90 outer end and engaging the cam. Retractile springs 185, 185 are fixed to the standard 98 at one end and fixed to the two blades of the shears at their outer ends causing a re-opening of the shears after a strip of weft 95 has been cut by the operation of the cams.

A gluing device 187 is mounted to operate upon the upper surface of the upper warp strips backwardly from the heald frames and adjacent to the weft clamp. With reference 100 to Fig. 6; the gluing device comprises a receptacle 188 adapted to contain glue having a gridiron valve 189 in the bottom which is operated by the pair of arms 190 fixed to the rock shaft 191 having a hand lever 192 105 extending upwardly through the top of the vessel.

A roller 193 is rotatably mounted in bearings 194, 195 below the valve 189 there being a funnel 196 disposed between the top of the 110 roller and the valve. A bevel gear 197 is fixed to the roller shaft. A second shaft 198 mounted in a bearing 199, carries a second bevel gear 200 meshing with the gear 197. The vessel carries two upper rollers 202, 202 115 and a lower roller 203, the lower roller being positively fixed to an extension of the shaft 198.

The upper rollers 202 and the lower roller 203 are adapted to run on a track 204 fixed 120 horizontally across the vertical standards 6, 6. The gluing device is operated transversely across the warp strips by a screw 205 operating in a nut 206 which is fixed to the vessel. The roller 193 has a slightly curved 125 surface to register with the bend of the warp due to the pressure of the roller thereon.

A second gluing device 207 is mounted to operate on the under surface of the lower set of warp strips. This under gluing means 130

comprises a vessel 208 adapted to contain glue and having a basin 209 fixed in the upper part and an elevator 210 carried on a shaft 211 rotatably mounted in bearings 212, 212. The elevator carries on its periphery buckets 213 adapted to elevate glue. The buckets have partitions dividing them into two compartments opening in opposite directions so that the glue will be raised with 10 the elevator running in either direction. The buckets will discharge the glue into the basin 209. The elevator also carries gear teeth upon a rim portion 214.

In the upper part of the vessel is rotatably 15 mounted in bearings 215 and 216 a roller 217 positioned with its lower part into the basin 209. Projecting from the side of the roller is a circle of pins 218 which engage the teeth on the rim 214 of the elevator. The roller shaft also carries a universal joint 219 connecting the roller shaft with a shaft 220 at the outer end of which is a gear 221, the shaft being carried in bearing 222. The under gluing means is provided with two 25 rollers 225 at the top and a roller 226 at the bottom in the same arrangement as the top gluing device 187, see Fig. 1.

The roller 225 is fixed to its shaft which rotates in bearing 227, and carries a gear 30 229 which meshes with the gear 221.

The under gluing device 207 is adapted to be mounted upon a track 230 fixed across the standards 6, 6 and is carried transversely of the warp strips by a screw 231 operating 35 in a nut 232 fixed to the vessel. The means for operating the screws 205 and 231 comprises a shaft 233 mounted in bearings 234 and 235, on the left hand side of the device, and having a bevel gear 236 fixed to the shaft 40 232 meshing with the bevel gear 89 on the transverse shaft 68. On the shaft 233 is a cam 237 having a grooved face. Astride the shaft 233 is a yoke 238 terminating at the top in a worm shaft 239 which extends upwardly slidably through the bearings 240 and 241 above and below a worm wheel 242 adapted to the screw 231 and through bearings 243 and 244 above and below a worm wheel 245 adapted to the screw 205, there 45 being a slow thread on that portion of the screws 205 and 231 which operates the gluing device transversely of the warp strips and a fast thread on that portion of the screws which engages the worm gears 242 and 245. A roller and pin 246 is carried by the upper end of the yoke 238 and adapted to operate in the groove of the cam 237 so that by rotation of the cam the worm shaft 239 is operated vertically thereby rotating 50 the worm wheels 242 and 245 which in turn rotate the screws 205 and 231 thus carrying the gluing devices back and forth across the warp strips.

It is here explained that in the present invention where wood ribbons comprise the

warp and weft of the fabric the shuttle must clamp upon and support the strips of weft through their entire length in order that they may be placed firmly in the weave and straight across the fabric. In order to effect 70 such a purpose the shuttle must have two separate movements, one in which the shuttle moves in and out of the loom as a shuttle, and the second in which the shuttle operates to place the weft strips in place in the weave. 75 This latter movement is exceptional for a shuttle and has been termed the "put" of the shuttle throughout this specification.

In the operation of the device, the two 80 gangs of reels 10 and 11 being wound full of wood strips, the wood strips being preferably of spruce and having a thickness more or less fourteen one thousands of an inch cut from lumber having any suitable length, the ends of the strips being glued together to 85 form a continuous ribbon; the individual reels are then mounted in position, carried upon the stub shafts 20.

The ends of each strip which comprises 90 the warp of the fabric to be woven is then carried through a tension spring 28 or 32, between the rollers 29 and 33, through one of the guides 30 or 34, between the rollers 31 and 35, through the heald frames 51 and 52, through the weft clamp 100, through the holding clamp 102 and through the feeder clamp 116. The machine is then rotated until the feeder clamp closes down upon the ends of the warp strips. A reel 131 carrying 95 a ribbon of the same material as the warp is mounted on the arm 130 of the shuttle carriage. This ribbon of wood comprises the weft for the fabric and its end is passed through the tension spring 133 over the roller 134, through the guide 135 and along 100 through the groove 158 of the shuttle. The clamping means of the shuttle is then 105 clamped upon the strip and the device is ready for operation.

A power belt is passed over a pulley 124 110 on the drive shaft 78 and by its rotation the cam 141 is rotated causing a vertical movement of the screw 147 and a rotation of the gear wheel 148 thereby effecting a reciprocation of the shuttle back and forth between the upper and lower strips of the warp which is held separated by the heald frames. The rotation of the main shaft also rotates the transverse shaft 68 through the pinion gear 82 on the main shaft rotating a gear 89 115 twice its size upon the transverse shaft. The bevel gear 89 on the left hand side of the device fixed to the transverse shaft therefore rotates the pinion gear 93, which is half its size, upon the shaft 90 thus causing the shaft 90 to rotate with the same speed as the drive shaft 78 and operating the pairs of cams 84 and 94, 85 and 95, 87 and 96, and 88 and 99 in unison except that they are operating in 120 reverse directions of rotation. Thus by the 130

rotation of the main shaft 78 and the shaft 90 the weft clamp, the holder clamp and the feeder clamp and the feeder means are operated. On the periphery of the cam 87, on the 5 main shaft, is a second cam 86 operating the shear 176 to cut the strips of weft at the proper time. The transverse shaft through the gear 89 also rotates the shaft 232 through the gear 235 and by its rotation through the 10 cam 230 and worm shaft 238, the worm gears 241 and 244 are rotated thus rotating the screws 205 and 230 thereby carrying the gluing means back and forth on the outer surfaces of the warp strips. By the rotation of 15 the transverse shaft 68 the heald frames are also operated through the cam 69, rack 73, gear 74, rock arm 65 and links 67 and 67A.

For a more exact description of the operation of the device, reference may be had to 20 the diagram in Fig. 20, in which a cycle of operation is represented in circles there being one circle for the operation of each member, in the device, functioning to form the cycle.

25 The device as illustrated in the drawings is shown in a position in advance of the start of the cycle to about the dotted line X in Fig. 20.

Beginning at the start of the cycle with 30 the shuttle out of the loom, with the shuttle clamp closed upon the strip of weft the shuttle being put backwardly or toward the head end of the loom, the heald frames having fully separated alternate strips of the warp, 35 the feeder clamp being closed upon the fabric and the feeder means having pulled the fabric more or less the width of a strip of the weft, the shear being open, the holding clamp open, the weft clamp open, the gluers positioned at the side of the warp; the cycle then 40 proceeds 90 degrees and carries the shuttle into the loom. Between 90 and 100 degrees of the cycle the shuttle is moved rearward putting the strip of weft firmly in the angle 45 of the warp strips and against the preceding strip of weft. The shuttle clamp opens at 140 degrees releasing the weft. The shuttle starts out of the loom at 145 degrees, travels 80 degrees, slackens its speed for 20 50 degrees and is completely out at 245 degrees of the cycle at which point the shuttle clamp is closed upon a new strip of weft. Between 280 and 300 degrees the shuttle is moved toward the head end of the device and remains in that position ready for 55 reentrance into the loom to the end of the cycle. The holding clamp is closed at 90 degrees, remaining closed to 245 degrees at which point it opens and remains open to the 60 end of the cycle. The weft clamp closes down upon the strip of weft just put by the shuttle at 140 degrees and remains closed to 265 degrees at which point it opens and remains so to the end of the cycle. The shear 65 remains open to 245 degrees of the cycle and

in the next 20 degrees thereof closes, cutting the strip of weft at the edge of the fabric and immediately opens again and remains so to the end of the cycle. The heald frames remain open to 225 degrees of the cycle and 70 then alternate their positions between that point and the end of the cycle. The gluers start across the strips of weft at the beginning of the cycle and complete the cross travel to the opposite side at 225 degrees of 75 the cycle and remain in that position to the end of the cycle. The feeder clamp becomes unclamped at 120 degrees of the cycle at which point it starts to move forwardly and is in a proper forward position at 145 degrees of the cycle. At 265 degrees of the cycle the feeder clamp becomes clamped upon the fabric and between that point and the end of the cycle the feeder clamp is moved backwardly pulling the fabric one 80 point.

Thus the cycle is completed and a fabric cross woven from ribbons of wood is formed.

The gluing means is operated on the surfaces of the warp strips to roll glue upon that surface only, which when the heald frames alternate their position becomes the inner surface which lies against the strip of weft, the gluers being preferably set to roll glue upon that surface of the warp 95 which will become engaged with the weft in the next succeeding cycle.

When any one of the reels 10 or 11 run out or become empty of warp, the two levers 22 on either side of the empty reel are 100 pressed together at the top end sliding the stub shafts 20 out of the central bore 17 thus releasing the reel after which a full reel may be put in its place and the stub shafts slipped partially into the bore by the 105 levers 22, the end of the warp carried in the new reel then being glued to the end of the loose warp strip in the loom.

The spring tension blades 28 and 32 are 110 designed to hold the warp firmly in normal position, the firmness of the hold being adjusted by the screw 46 so that when the warp is pulled into the device the tension springs will resist the pull and bend in the direction of the pull which bending lengthens the inside blade 36 relative to the outside blade 37 causing a widening of the slot in the end of the spring. In this manner the blades are always resisting the travel of the warp holding and slipping backwardly and taking up the slack thrown into the warp by the alternations of the heald and should an obstruction occur along a strip of warp, for instance, such as a lap formed in the gluing of the strips together, 125 the spring tension would be pulled and bent until the slot became wide enough to release and pass the widened portion.

The wood fabric comprising the product of the device is intended to be used in a 130

single sheet for some purposes or it may be laminated with other sheets of the same material more or less corrugated being interlaid again with flat sheets of the material 5 so that a thickness of several layers may be built up having a great stiffness. Such a product, it is intended, is to be used for the surfaces or covering of aeroplane wings and possibly for automobile tops and the like.

10 The strips of wood used in the manufacture of the above article are preferably cut from the spruce lumber by special machinery and for ordinary purposes have a width of 1 inch and a thickness of about fourteen 15 thousandths of an inch, they being glued together end on end to form a continuous ribbon of the material.

It is obvious that the arrangement of the 20 different parts of the invention relative to one another might be altered and the means for operating them might be modified and that various other changes might be made in the invention as set forth without departing from the spirit thereof as claimed.

25 I claim:

1. In a wood weaving loom, in combination, means for feeding a warp composed of strips of wood, means for alternately crossing alternate strips of warp, a shuttle adapted to grip throughout their length and carry thin strips of wood comprising a weft in between the crossed strips of warp, means for putting the shuttle to place the strip of weft in position in the weave, means for releasing the weft strip from the shuttle and means for operating the shuttle in and out of the loom.

2. In combination, in a wood weaving loom, means for feeding a warp composed 40 of wood ribbons, means for healding the warp, a shuttle adapted to travel in and out of the loom to grip throughout its length and carry into the loom a wood ribbon forming a weft, means for moving the shuttle 45 to put the weft strip tightly in place in the weave, a clamp for holding the weave against the put of the shuttle, a second clamp for gripping the weave to hold the weft strip put by the shuttle and means 50 for pulling the fabric along a proper distance for each cycle of the loom.

3. In a wood weaving loom, a shuttle mounted to travel in and out of the loom comprising a member for supporting the 55 shuttle in proper guides, an outwardly extending member having a clamp adapted to bear upon and hold throughout its length a thin strip of wood comprising a weft and means mounted upon the shuttle for opening and closing the clamp.

4. In a wood weaving loom, a shuttle mounted to travel in and out of the loom comprising a member for supporting the shuttle in proper guides, an outwardly extending

member having a weft clamp adapted to 65 bear upon and hold a thin strip of weft, blades mounted upon the shuttle and bearing upon one side of the clamp, and a rocking cam shaft mounted on the shuttle having cams positioned to operate upon the 70 blades whereby the rocking of the cam shaft will open and close the weft clamp of the shuttle.

5. In a wood weaving loom, in combination, means for feeding warp composed of 75 thin strips of wood, means for retaining a flexible tension on the warp, means for healding the warp strips, a shuttle adapted to travel in and out between the healded warp and to carry a thin strip of wood into 80 the loom forming a weft, means for moving the shuttle to put the weft strip tightly in place in the weave, a clamp for holding the weave against the put of the shuttle, a second clamp for gripping the weave to hold the weft strip put by the shuttle, and means for pulling the fabric a proper distance out of the loom for each cycle thereof.

6. In combination, in a wood weaving loom, means for feeding warp composed of 90 thin strips of wood, means for healding the warp strips, a shuttle adapted to travel in and out between the healded warp and to carry a thin strip of wood into the loom forming a weft, means for moving the shuttle to put the weft strip tightly in place in the weave, a clamp for holding the weave against the put of the shuttle, a second clamp for gripping the weave to hold the weft strip put by the shuttle, gluing means operating to spread glue upon that part only of the surface of the warp in one cycle which becomes engaged with and lies upon the weft in a succeeding cycle and a discharge means for the loom.

7. A gang of reels for a wood weaving loom adapted to carry a warp composed of strips of wood, comprising reels having hubs carrying central bores, a bar for supporting the gang of reels having extending arms, 110 one for each reel, the arms terminating in bearings at their outer ends adapted to slidably carry stub shafts, the shafts extending slightly from either side of the bearings and having annular recesses at the centers, 115 levers pivotally mounted upon the bar and extending downwardly and engaging the annular recesses of the stub shafts, spring pockets in the ends of the arms carrying retractile springs and balls adapted to partially enter the annular recesses of the stub shafts whereby the shafts are held from drifting away from a central position, the shafts being of such length that by the operation of the levers they may be withdrawn 120 from any individual reel whereby the reel may be disengaged from the gang.

8. In a wood weaving machine, in combi-

nation, a gang of reels adapted to carry half of a warp, a second gang of reels staggered relative to the first gang adapted to carry the other half of the warp, the two gangs 5 of reels being mounted in a proper frame, spring tension blades, one for each strip of the warp adapted to retain a backward tension upon the warp, guide means for the warp strips positioned beyond the spring 10 tension blades, heald frames mounted to cross and recross alternate strips of the warp, means for slidably operating the heald frames, a shuttle carriage adapted to move within narrow limits longitudinally of the 15 loom, a shuttle mounted upon the carriage adapted to carry wood strips comprising a weft into the loom, means for clamping and unclamping the wood strips in the shuttle, an outer bearing for the shuttle on the opposite 20 side of the loom from the shuttle carriage, means for moving the shuttle carriage and the outer shuttle bearing to move the shuttle whereby a strip of weft is put tightly into the weave, means for moving 25 the shuttle back and forth in and out of the loom, a clamp for holding the weave against the put of the shuttle, a clamp bearing upon the weave to hold the strip of weft put by the shuttle, a shear operating 30 to cut the strips of weft at the edge of the fabric, gluing means for rolling glue upon that part only of the warp which when the heald frames alternate the strips of warp is crossed with and lies upon the strip of 35 weft, means for pulling the fabric a proper

distance for each cycle of the loom, and a weft reel for the shuttle carriage.

9. In a tension spring for a wood weaving loom, a curved outer blade terminating in a tongue, a curved inner blade having an outer end bent up to the level of the curved outer blade and having ears bent up around the end of the outer blade whereby the outer blade is slidably mounted upon the inner blade and having a slot cut in the end the width of the tongue so that the tongue may cover part of the slot opening, the inner blade being adapted to be positively mounted on a proper standard and the outer blade being adapted to be advanced along the inner blade to vary the width of the slot opening.

10. In a wood weaving loom, in combination, means for feeding a warp composed of strips of wood, means for healding the warp 55 strips, a shuttle adapted to grip throughout its length and carry into the loom thin strips of wood, comprising a weft, means for putting the shuttle to place the weft firmly in position in the weave, gluing means adapted 60 to spread glue upon that part only of the surface of the warp in one cycle of the loom which becomes engaged with and lies upon the weft in a succeeding cycle thereof, means for operating the shuttle in and out 65 of the loom, and a discharge means for the loom.

In testimony whereof I have signed my name to this specification.

OSMOND T. BELCHER.
